LOOM BINDER ADJUSTING MECHANISM

Walter A. Sherwood, Hempstead, N.Y., assignor, by
mesne assignments, to Chandler Evans Corporation,
West Hartford, Conn., a corporation of Delaware

Filed Mar. 27, 1959, Ser. No. 802,455

5 Claims. (Cl. 139—185)

This invention relates to loom binder adjusting mechanism, and particularly to such mechanism for adjusting the position of a movable part of the shuttle box, constituting a binder, so as to stop the shuttle accurately in a desired position in the box.

It is an object of the invention to provide such a means for manually adjusting the binder while the loom is in operation in order to permit continuous observation of the results of the adjustment while it is being made.

The adjusting mechanism is shown herein as designed for use in cooperation with a hydraulic shuttle check, such as the check shown and described in Sherwood Patent No. 2,818,884, issued January 7, 1958, by means of which the entire deceleration of the shuttle may be effected frictionally.

A practical embodiment of the invention is shown in the accompanying drawings wherein:

Fig. 1 represents a top plan view of the shuttle box, adjustable binder and check, parts being in horizontal section and parts being broken away;

Fig. 2 represents a vertical section, taken on the line II—II of Fig. 1, parts being shown in elevation and parts being broken away;

Fig. 3 represents a vertical section, taken on the line III—III of Fig. 1; and

Fig. 4 represents a detail perspective view of the slideable adjusting platform and its ramp.

Referring to the drawings, the shuttle box is shown as comprising a floor plate 1, a leather-faced fixed binder 2 and a movable binder 3 pivotally mounted on the bolt 4. Said bolt may be simply screwed into the floor plate 1 but is preferably caused to pass through holes in the bracket 5 and land 6 projecting from a fixed side plate 7 which is, in turn, secured to the floor plate 1. The shuttle box is shown as being of the stationary type, securely mounted on the loom frame, part of which is indicated at 8. The side plate 7 is cut away, at least in the region spaced from the bolt mounting brackets, to permit cooperation of the head 38 of a hydraulic check 30 with the movable binder 3, the preferred type of check being shown and described in Patent No. 2,818,884, mentioned above.

The movable binder 3 is shown (Fig. 3) as having a generally T-shaped cross-section, the main body portion 9 lying vertically and being faced with a leather covering 10 on its working surface and reinforced by a horizontally projecting rib 11 on its back surface. At the pivot end the rib is thickened as indicated at 12, and at the opposite end (nearest the picker 13) there is provided a more or less rectangular block 14 the vertical dimension of which corresponds to that of the body portion 9 and the horizontal dimension perpendicular to the plane of said portion being approximately that of the rib 11.

The rib 11 is cut away adjacent the block 14 to provide a ramp 15 which slants, in a horizontal plane, from a maximum spacing nearest the block 14 to a minimum spacing farthest from said block, considered with respect

5 to the working face of the binder. The block 14 is traversed horizontally by a bore 16 the axis of which lies in the vertical plane of the ramp 15 but at a level midway between the lower surface of the rib 11 and the bottom plane of the binder, the bore being preferably enlarged slightly at its end nearer the ramp to form an annular shoulder 17.

10 A platform 18, preferably in the form of a solid rectangular block, is provided with a groove 19 of varying depth and of a size to receive the ramp 15 with a free sliding fit, the groove being deepest at the end of the platform toward the block 14 and shallowest at the opposite end. The platform 18 is also traversed by a threaded bore 20, the axis of which corresponds to the axis of the bore 16 when the platform is fitted on the ramp with the ramp filling the groove 19. The vertical surface 21 of the platform lies approximately perpendicular to the axis of the check 30 and is of such length that it can be contacted by the head 38 of such check in any position of the platform on the ramp.

15 The platform is designed to be operated by means of a screw 22 having a threaded end engaging the threaded bore 20, an annular shoulder 23 adapted to fit freely against the shoulder 17 in the enlarged end of the bore 16 and to serve as a stop, and a small diameter end 24 adapted to fit in the bored stem 25 of a turning knob 26 where it may be pinned, screwed or otherwise firmly fixed. The stem 25 is provided also with an enlarged bore 27 to receive a spring 28 which is compressed between the stem and a side of the block 14, thus holding the shoulder 23 against the shoulder 17. From this description it will be apparent that the turning of the knob 26 also turns the screw 22 engaging the platform, which is thus moved along the ramp toward or away from the block 14. The slope of the ramp, corresponding to the varying depth of the groove 19, causes the platform to act as a wedge, holding the movable binder 3, in the arrest position of the check, at distances from the fixed binder 2 which are determined by the position of the platform on the ramp. For example, referring to Fig. 1, when the platform is moved toward the left the spacing between the binders is enlarged and when the platform is moved toward the right the spacing is narrowed.

20 It is the aim of the operator to have the binders arrest the flight of the shuttle S at a point just short of the picker face in its retracted position (so that the picker may not have to absorb any of the shock of stopping the shuttle—or at least any substantial part of such shock). The hydraulic check of Patent No. 2,818,884, operating through the binders shown in said patent, and stop the shuttle very accurately at a desired point according to the initial adjustment of the check and under the conditions existing when such initial adjustment is made. However, the conditions start changing the instant the loom is put in operation: the leather facings start to become worn and/or polished, the temperatures of the mechanical parts and of the hydraulic fluid tend to vary, the total weight of the shuttle and its load varies constantly, the drag of the yarn may vary, and the ambient temperature and humidity cannot readily be maintained constant. The interaction of such variables may, fortuitously, permit satisfactory operation of the binders for substantial periods of time, but, on the other hand, it is much more likely that inaccurate stopping of the shuttle will be observed quite early in its operation. With the provision of the adjusting means shown and described herein, optimum operation can be assured constantly on a purely empirical basis; the operator need not consider why the shuttle starts to show tendencies toward short or long stopping, but can observe the operation from time to time and correct any such tendencies as soon as they appear, merely by turning the knob

26 one way or the other until the shuttle is again stopping at the proper point. Since the adjustment can be effected in a second or two, it is quite unimportant whether the changing conditions require corrections to be made every few minutes or whether the operation can be stabilized for hours at a time. The operation of the loom is not interrupted, the result of the adjustment can be instantly and continuously observed, and better boxing of the shuttle is achieved, with increased binder and picker life.

The planes of the ramp-engaging bottom of the groove 19 and the surface 21 (the effective surfaces of the "wedge-like element") are disposed so nearly perpendicular to the direction of outward movement of the binder 3 against the check head 38 that the component of force perpendicular to said direction is insufficient to overcome the friction of the platform against the ramp and check head, hence the wedge-like platform has no tendency to be displaced from its adjusted position. Additionally, the adjusting screw 22 is restrained from free turning by the engagement of the shoulder 23 against shoulder 17 under the force of spring 28.

While the adjusting mechanism is referred to as being used with a stationary shuttle box, fixed to the loom frame, it will be understood that it could also be used advantageously in connection with a shuttle box mounted on the lay; in that case, however, the adjustment of the screw would normally require temporary stoppage of the loom.

Since looms vary considerably in their structural details and may include parts or auxiliary mechanisms in the vicinity of the shuttle boxes which will require detail changes in the form, construction and arrangement of the binders, it must be recognized that the binders and adjusting mechanism shown and described herein are of a simple and basic nature, subject to change in details as may be required by their environment without departing from the spirit and scope of the invention.

What we claim is:

1. A loom binder adjusting mechanism comprising, a movable binder pivotally mounted at one end and having a working surface adapted to constitute one side of a

shuttle box, resilient check means adapted to restrict outward movement of said binder, a wedge-like element interposed between said binder and said check means and carried by said binder intermediate the ends thereof, and adjusting means located at the opposite end of the binder from its pivot end and adapted to slide said wedge-like element longitudinally of said binder.

5 2. A loom binder adjusting mechanism according to claim 1 in which the movable binder is provided with a 10 ramp having a surface located at progressively varying distances from the working surface of the binder, and in which the wedge-like element is slidably mounted on said ramp.

15 3. A loom binder adjusting mechanism according to claim 2 in which the ramp-engaging and check-engaging surfaces of the wedge-like element lie so nearly perpendicular to the direction of outward movement of the movable binder against the check that the components of friction between the ramp, the wedge-like element and 20 the check are greater than the component of force acting on said wedge-like element perpendicular to said direction and resulting from the wedge-like form of said element.

25 4. A loom binder adjusting mechanism according to claim 1 in which the movable binder is provided with a horizontal longitudinal rib, at least part of which constitutes a ramp having a surface located at progressively varying distances from the working surface of the binder, in which the wedge-like element is slidably mounted on 30 said ramp and in which the adjusting means includes a manually operable screw engaging the wedge-like element.

35 5. A loom binder adjusting mechanism according to claim 4 in which the wedge-like element is provided with a threaded bore the axis of which is parallel to said surface of said ramp and in which the manually operable screw engages said threaded bore.
